UNITED STATES PATENT OFFICE.

MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,147,025.

Specification of Letters Patent. Patented July 20, 1915.

Application filed April 5, 1913. Serial No. 759,029.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part 10 of this specification.

The invention has for one of its objects the provision of means controlled by each selector switch which is the first to select a responsive device for holding a succeeding responsive device hunting selector switch in position to connect the same responsive device with the calling line operating such succeeding selector switch and operator controlled means for freeing the selected responsive device from the first selector switch and bringing it into connection with the second selector switch and thereby with the calling line operating the second selector switch.

25 The invention has for another of its objects the provision of a group of link connectors at the exchange for each operator to whose use it is adapted in connecting calling and called lines, signal devices for the link connectors of each group, and means governed by equipment of the link connectors for causing such signal devices to operate when their link connectors are idle and to restore the signal devices when their link 35 connectors are taken for use.

I will explain my invention more fully by reference to the accompanying drawings showing the preferred embodiment thereof and in which—

40 Figure is a very general diagrammatic view illustrating, in simple form, the essential features of the invention as they are preferably embodied; and Figs. 2 and 3, taken collectively end to end with the discontinued conductors at the right hand end of Fig. 2 in alignment with the discontinued conductors at the left hand of Fig. 3, illustrate the preferred embodiment of the invention in diagrammatic detail.

50 Like parts are indicated by similar characters of reference throughout the different figures.

Referring first more particularly to Fig. 1, I have there indicated two subscribers' 55 stations 120 and 190 each having a selector

switch A, B individual to its line but to which individual selector switches the invention is not to be limited. These selector switches have wipers which move over waiting contacts that pertain to telephone line 60 extensions C, D which are peculiar to calling lines and are included in connections between calling and called subscribers only at the calling line ends of such connections. There are preferably fifty extensions C or 65 D apportioned to the use of each operator and the extensions of each operator's group are each provided with multiplied waiting contacts distributed among the switches of such operator. The wipers of the switches 70 E or F, selected for use by the operator, are moved by operator controlled means over the waiting contact terminals of the calling line extensions, these switches being individual to link connectors whose connecting 75 ends are here shown as terminating in connecting plugs G, the plugs G belonging to switches E being at one operator's position and the plugs G pertaining to the switches 80 F being at another operator's position, there 85 being desirably twenty five such plugs to each operator's position and, of course, as many switches. The calling line extensions C, D are here shown as being divided into groups each group being individual to an 85 operator's position and the selector switches A, B, in addition to selecting idle extensions C, D, will also select the corresponding calling line operated operator's responsive device which may be in the form of a signal 90 lamp H or an operator's telephone I, or both of these classes of devices. When a calling subscriber selects an idle calling line extension and the responsive device peculiar to the operator's position to which the selected extension belongs, the operator will 95 select an idle link connector for joining the calling line with the desired line and will cause the operation of the switch E or F by means of a key K individual to such switch 100 and the link connector having such switch to connect the corresponding connecting plug G with the calling line. The operator will complete the connection by inserting the plug G that has become connected with the 105 calling line into a jack L of the called line multiplied in her position. The responsive device I, is provided with two relays M either of which, when energized, renders the responsive device I unselectable. The se- 110

lector switch first operating to energize either relay M connects the responsive device I with the calling line of such switch, there being means (not indicated in Fig. 1) whereby a second hunting selector switch may be arrested in association with the second relay M in readiness to connect the previously selected responsive device I with the second calling line when the responsive device has been freed by the operator when the plug G has become connected with the first calling line, relay mechanism N, operator controlled, performing this latter function.

Each link connector having a plug G also has a signal device O individual thereto. When a link connector is taken for use the operator's relay P individual thereto effaces the associate signal at O through the inter-mediation of a switching device Q whose motor magnet R is operated whenever a relay P is energized. A switching device S governed by an operator's key T may occupy one position so that but one signal lamp O may be displayed at a time at one position irrespective of the number of idle links at such position or so that there may be as many signals displayed at O as there are idle links individual thereto. As the system is equipped the link connectors may be idle though their plugs G are inserted in jacks of lines at whose substations the receivers have been restored to their switch hooks.

Referring now more particularly to Figs. 2 and 3, I have shown well known equipment at telephone stations 120 and 190, the equipment at each station including a telephone receiver switch hook 1, a telephone receiver 2, a telephone transmitter 3, a call bell 4, and a condenser 5, the switch hook having a normal contact for connecting the associate bell and condenser 5 in bridge of its line and an alternate contact for connecting the telephone transmitter 3 in bridge of its line, the receiver being in a closed local secondary circuit in inductive relation to the transmitter circuit. When a subscriber, say at station 120, initiates a call he removes his telephone receiver from its switch hook to engage the switch hook with its alternate contact whereby a circuit is established which is traceable from the upper grounded coil of the differential cutoff relay 6, the intermediate armature switch of the switch-ing relay 7 and its normal contact, both sides of the calling line by way of the transmitter bridge at the calling station, the lower armature switch of the switching relay 7 and its normal contact, the lower winding of the cutoff relay 6, the line relay 8, to the grounded common battery 9. The armature switch of the line relay 8 is now attracted to establish a circuit traceable from this grounded armature switch of this relay, the contact engaged by this switch, the motor

magnet 10, the circuit interrupter 11, to the grounded common battery 9. The motor magnet 10 steps the wipers 12, 13, 14 of the selector switch A of the calling line around until the wiper 14 engages a contact that is connected with the grounded battery 9, whereupon circuit is established traceable from the grounded battery 9, the armature switch of relay 15 and its normal contact, the armature switch immediately above the winding of magnet N, the contact engaged by the wiper 14, the armature of motor magnet 10 and its contact, the winding of relay 7 to ground. The relay 7 establishes a locking circuit for itself traceable from its grounded terminal through its winding, its intermediate armature switch of the left hand alternate contact of this armature switch, both sides of the calling line, the lower armature switch of relay 7, the alternate contact of this armature switch, the wiper 13, the upper intermediate armature switch of relay N and its normal follow-up contact, the relay 16, the relay 15, to the common grounded battery 9. The circuit for the line relay 8 is now opened at the normal contacts of the two lower armature switches of relay 7, whereby the armature switch of relay 8 is released to open the circuit for motor magnet permitting the wipers 12, 13, 14 to remain at rest. The uppermost armature switch of relay 7 is grounded through a common resistance 17 and the common grounded battery 9 so as to place battery in connection with the tip line springs of the jacks L pertaining to the calling lines to make the calling line busy. The relay 15 is now energized to cause its armature to engage its alternate contacts to establish circuits through the calling signal or responsive device H to attract the selected operator's attention or for purposes of super-
vision and through the relay M to connect the selected operator's telephone I with the calling line.

The circuit for the element H is traceable directly to the grounded battery 9 connected with the armature switch of relay 15. The circuit for the relay M is traceable from the grounded battery 9, the armature switch of relay 15, the right hand alternate contact of this armature switch, the winding of relay M, the lowermost armature switch of the companion relay M and the normal contact of this armature switch to ground. The first relay M is energized to attract this armature switch, the two upper most armature switches serving to connect the operator's telephone in bridge of the selected extension C and consequently in bridge of the calling line whereupon conversation may be held between the calling subscriber and the selected operator. At this point it may be well to mention the equipment by which the selected responsive device I is held for connection

with a new calling line by the selector switch thereof. The lower armature switch of the energized relay M is separated from its normal contact to open the circuit of the companion relay M (this being true irrespective of which relay M is the first to be energized) so that another selector switch will not connect the previously selected responsive device I with its calling line. In the case of a second calling line another relay 15 companion to the previously selected relay 15 is energized to establish a signaling circuit for its associate lamp H and partially to establish circuit for its associate relay M so that when the first relay M is deenergized the second relay M will at once be energized to connect the second calling line with the responsive device I that was just previously connected with the first calling line. Each relay 15 constitutes a means for holding a succeeding or second operating responsive device hunting selector switch in position to connect the responsive device I with the calling line operating such succeeding selector switch when such responsive device is freed from its connection with the first calling line. The normal contact of the armature switch of each relay 15 is common to the extensions of the group of calling line extensions 30 to which group such relay 15 is individual. As the system is disclosed there are two such relays 15 for each group of calling line extensions C or D in each operator's position and each relay 15 has apportioned to it a half of the calling line extensions apportioned to the use of the operator having such relay 15, a pair of relays 15 being apportioned to each operator. Thus when any relay 15 is energized its twenty-five associate 40 calling line extensions are rendered busy until such relay is deenergized.

The operator, having received the number of the desired line, say station 190, selects an idle plug G for use and inserts the same 45 within a jack L belonging to the desired line without testing. In order that the system may be adapted to better line service calling keys are employed but to the employment of which the invention is not to be limited. I have shown five calling keys K adapted to connect generators 18, 19, 20, 21 and 22 of differing frequencies with the called lines, that key K being depressed which will associate the particular generator that is adapted 50 to operate the bell at the desired station with such bell. In the case of the single station 190, the first key K to the left may assume to be the key for operating the signal bell at station 190.

60 Where calling keys are employed they are desirably given additional functions which would otherwise be performed by other operator's equipment. That is if the telephone is upon its switch hook at its station, a circuit is closed at 24 as a consequence of the

depression of any of the keys K, each key engaging a pin 25¹ upon a bar 26, which bar is in circuit closing relation to the switch 24. As soon as the bar 26 has closed the switch 24 the actuated pin 25¹ engages the upper 70 notch in the key plunger so as then to open the switch. The circuit closed by the switch 24 is traceable from the grounded relay 25, the switch 24, the sluggishly operating relay 26¹, to the grounded battery 9. The relay 26¹ momentarily holds its armature switches and then releases the same, a circuit being established by the upper armature switch traceable from ground, said switch, the right hand contact of this switch, the relay 27, the 75 uppermost armature switch of relay 28 and its normal follow-up contact, the tip of the employed plug G, the tip line spring of the called line jack, the upper winding of the differential cutoff relay 6 belonging to the 80 called line, to ground. The relay 27 is not now operated as it is not now connected with battery. The relay 26¹ establishes another circuit traceable from its grounded upper armature switch, the left hand contact 85 of this switch, the winding of sluggishly operating relay 29, the lower armature switch of sluggishly operating relay 30 and its normal contact, to the grounded common battery 9. The relay 29 establishes a locking circuit for itself traceable from the upper grounded armature switch of this relay, the left hand contact of this armature switch, the winding of the relay 29, to the 90 grounded battery 9 by way of the lower 100 armature switch of relay 30 and its normal contact. The lower armature switch of the relay 29 establishes a circuit traceable from the grounded common battery 9, the resistance 31, the lower armature switch of relay 105 29, the left hand contact of this armature switch, the lower armature switch of relay 26¹, the contact of this armature switch, the lower armature switch of relay 27, the normal contact of this armature switch, the 110 winding of relay 28, the uppermost armature switch of relay 32, the contact of this armature switch, to ground. The relay 28 establishes a locking circuit for itself traceable from the grounded battery 9, the resistance 31, the lower armature switch of relay 29 and the right hand contact of this 115 armature switch, the armature switch of relay 33, the normal contact of this armature switch, the lowermost armature switch of relay 28, the contact of this armature switch, the winding of relay 28, the top armature switch of relay 32, to the grounded contact of this armature switch. The 120 armature switches of relay 28 are operated to engage their alternate contacts to establish a ringing circuit over the desired line (it being assumed that the desired line is idle) which ringing circuit is traceable from the grounded pole of the em- 125 130

ployed ringing current generator, the right hand pair of contacts of the depressed key, the normally closed contacts of the remaining keys that happen to be to the right of the depressed key, the winding of relay 33, the intermediate armature switch of relay 28 and its alternate contact, the sleeve of the employed plug G, the sleeve line spring of the jack receiving this plug, the armature switch of the called line cutoff relay 6 and its alternate contact, the lowermost armature switch of the called line switching relay 7, and its normal contact, the bell at the called station, the intermediate armature switch of said relay 7, the normal contact of this armature switch, the tip spring of the jack L receiving the plug G, the tip of this plug, the top armature switch of relay 28 and its alternate contact, the primary test 10 tone producing coil 34, to the grounded battery 9. Current finding path from the battery 9 through coil 34 traverses the upper grounded winding of the called subscriber's cutoff relay 6 to energize this relay to attract its armature into engagement with its alternate contact to complete the sleeve side of the called line and also to open the circuit of the line relay 8 at the normal contact of the armature switch of relay 6 to open the 15 circuit of the called subscriber's motor magnet 10 so that when the called subscriber responds he will not set his selector switch B into operation.

When the relay 29 is energized its upper armature switch establishes a circuit by way of its right hand contact that includes the upper armature switch of relay 30 and its contact, the motor magnet 35, the interrupter 36, and the grounded battery 9. The 20 motor magnet 35 will drive the wipers 37, 38, 39 around until the wiper 39 encounters a waiting contact that is connected with battery and is free of direct ground connection, this being a condition that is imposed by the operator upon a calling line extension that has become connected with the calling line and which is to be connected with the employed plug G. The means shown for placing this condition upon the waiting contact 25 of the calling line to be engaged by the wiper 39 happens to be an operator's key K that causes the closure of the circuit of the relay 25 momentarily. The relay 25 momentarily closes a circuit traceable from this 30 grounded armature switch, the lower contact of this switch, the relay 40, to the grounded battery 9. The relay 40 establishes a locking circuit for itself traceable from the grounded battery 9, the lower armature switch of relay 40, the contact of this switch, the left hand alternate contact of the bottom armature switch of the operated relay M, to ground by way of said armature switch. The upper armature switch of relay 40 establishes circuit 35 traceable from the grounded battery 9,

this armature switch, the contact thereof, the lower intermediate armature switch of the employed relay M, the contact of this armature switch, the armature switch of the relay 16, the contact of this armature switch, the winding of relay N, the contact engaged by the wiper 39, the wiper 39 when engaging this contact (the battery connection thus established upon this contact being established by the operator for the purpose of arresting the 70 wiper 39 in engagement with this contact), the winding of sluggishly operating relay 30, the armature switch of motor magnet 35, and its contact, to ground. The lower armature switch of relay 30 is attracted to leave 80 its normal contact to open the locking circuit for the relay 29 to release this relay, the upper armature switch of relay 29 opening the circuit of the motor magnet 35 as the right hand contact of this armature switch 85 whereby the wipers 37, 38 and 39 are permitted to remain in the positions to which they have been brought when the wiper 39 is in engagement with the waiting contact upon which battery was placed by the operator at the armature switch of relay 25. The lower armature switch of energized relay 30 establishes a circuit traceable from the grounded battery 9, this armature switch, the alternate contact of this switch, the 90 winding of relay P to ground. The relay P established a locking circuit for itself traceable from its grounded winding, through the armature switch of relay 41 and its left hand contact, the resistance 42, to the grounded battery 9, the relay P having established a circuit for the relay 41 traceable from the grounded battery 9, the winding of relay 41, the armature switch immediately below the winding of relay P, the contact engaged by this armature switch, the wiper 38, the contact of the employed calling line extension engaged by this wiper, the upper intermediate armature switch of relay N, the alternate contact of this armature switch, the wiper 13 of the calling line, the waiting contact engaged by this wiper, thence by obvious connections over both sides of the calling line to the intermediate armature switch of the calling line switching relay 7, the left hand alternate contact of this armature switch to said relay 7 which is grounded, the circuit thus traced being possible owing to the energization of the relay N previously traced through the wiper 39, the relay N having established a locking circuit for itself traceable from the grounded battery 9, the bottom armature switch of this relay, the contact of this armature switch, the winding of relay N, the waiting contact engaged by the wiper 39, said wiper 39, the next to the bottom armature switch of relay P, the contact of this armature switch, to ground. The sluggish relay 41¹ 105 is provided for maintaining the battery circuit 110 115 120 125 130

cuit for switching relay 7 while relays N and P are being operated. When relay N is energized it opens the circuit for the associate relays 15 and 16 at next to the top armature switch of relay N and the normal follow-up contact of this switch whereupon relay 15 releases its associate magnet M to free the previously selected operator's responsive device or telephone I.

10 The locking circuit for relay 40 is opened by the released relay M at its bottom armature switch and its left hand alternate contact whereby the selected operator's equipment is restored to selectable condition with
 15 regard to another calling line. The calling subscriber will know that the called party is being signaled owing to the transmission of ringing current from the coil 34 to the coil 43, the secondary circuit being traceable from ground, the common battery 9, the secondary coil 43, the relay 44 (which is not energized by the induced current), the condenser 45, the armature switch immediately below the relay P and its contact,
 20 the wiper 38, thence by obvious connections to and through the calling subscriber's receiver. When the called subscriber responds he substitutes a low resistance telephone bridge for the high resistance bell bridge
 25 permitting sufficient current to flow from the employed ringing generator through the relay 33 to energize this relay to open the locking circuit of the magnet 28 at the normal contact of the armature switch of relay
 30 33 whereby the relay 28 is deenergized to permit its two upper armature switches to engage their normal contacts. When circuit through relay 33 is completed it momentarily establishes circuit at the alternate
 35 contact of this armature switch through the sluggishly operating relay 46, the armature switch of relay 46 momentarily connecting the battery 9 with the tip of the employed plug G so as to prevent faulty operation of the called subscriber's cutoff relay
 40 6. A circuit is established through the relay 44 traceable from the grounded battery 9, the secondary coil 43, the relay 44, the middle armature switch of relay P and its
 45 contact, the lower intermediate armature switch of relay 32 and its normal contact, the intermediate armature switch of relay 28 and its normal contact, the sleeve of the employed plug G, the sleeve line spring of
 50 the jack L engaging this plug, the armature switch of the called subscriber's cutoff relay 6 and his alternate contact, thence by obvious connections over both sides of the called line to the grounded upper coil of
 55 the called subscriber's cutoff relay 6, the calling and called subscribers now being in talking relation, as will be apparent. When the subscribers are through conversation they will restore their receivers upon their switch
 60 hooks and if the called subscriber restores
 65

his receiver first relay 44 will be deenergized owing to the breakage of the circuit at the called station, whereupon a momentary circuit is established traceable from the grounded battery 9, the resistance 42, the 70 armature switch of relay 44 and its normal contact, the armature switch of sluggishly operating relay 47 and its normal follow-up contact, the alternate contact of this armature switch, the relay 32, to ground, the 75 connections including the armature switch of relay 47 and its two contacts occurring during the release of this armature switch, circuit for the relay 47 having previously been established by way of the right hand 80 alternate contact of the armature switch of relay 44. A locking circuit is established for the relay 32 traceable from ground, the winding of this relay, the bottom armature switch of relay 32 and its contact, the armature switch of relay 41 and its right hand contact, the resistance 42, to the grounded battery 9. When relay 32 is energized its intermediate armature switches engage their alternate contacts to include the secondary 90 coil 48 in bridge of the calling line, a test tone being induced in this coil from the primary coil 49 that is included in a local circuit with an interrupter 50 whereby the calling subscriber is informed that the called 95 subscriber has replaced his receiver upon its switch hook. The called subscriber is now placed in control of his own line relay 8 owing to the deenergization of his cutoff relay 6. At this stage of the operation the 100 talking strands leading to the plug G are broken at the intermediate armature switches of relay 32 so as to relieve the portions of the talking strands intervening between this plug and these armature 105 switches free of bridge connections whereby the previously busy and now free called line may be called over a new connection, the plug G being permitted to remain in the jack of the called line. When the calling 110 subscriber restores his receiver upon his switch hook circuit for his relay 7 and the relay 41 is opened at the alternate contact of the calling subscriber's switch hook, whereupon their armature-switches are restored to normal, the wipers 12, 13 and 14 remaining in engagement with the contacts that they previously came in contact with, this being possible owing to the separation 115 of the wipers 12, 13 and 14 from the calling line equipment at the lower armature switches of relay 7 and the armature switch of relay 10.

The wipers 12, 13 and 14 of the calling line selector switches do not, in the embodiment of the invention herein shown, restore to normal but continue to rotate in a single direction only and upon release they simply remain in engagement with the contacts with which they were previously brought 120 125 130

into connection. This is a very advantageous feature as the equipment of the selector switch is simplified and the wipers are enabled to continue their rotation until 5 they engage idle waiting contacts, such rotation being continued if it should happen that all of the waiting contacts are busy and lasting until a set is free. When the calling subscriber restores his telephone 10 upon his switch hook the relay 41 is de-energized to open the locking circuit for the relay 32 at the right hand alternate contact of the armature switch of relay 41. A circuit path for relay P is opened at the left 15 hand contact of the armature switch of relay 41 controlled by the calling subscriber and another and remaining circuit path for this relay P is opened at the left hand alternate contact of the armature switch of relay 20 44, which relay is de-energized with the called subscriber restores his receiver upon its switch hook. Relay P is thus under joint control of the calling and called subscriber when both subscribers have restored their 25 receivers upon their switch hooks this relay P is de-energized to release its armature switches, the three upper armature switches of this relay P being restored to normal to disconnect the wipers 37, and 38 from the 30 link at the relay P and also to disconnect the plug G from the wipers 37 and 38 and armature switches of relay P whereby the wipers 37 38 and 39 and the plug G are freed from all link connector bridges so 35 that said plug G may remain, if desired, in the jack in which it was placed instead of being withdrawn by the operator when connection between subscribers is through.

Assuming that the desired station 190 is 40 busy, that is that the receiver is free of its hook at this station, the plug G having been inserted in the jack of the desired line, an operation which occurs without any testing, a depression of a ringing key K will not 45 cause the impression of signaling current upon the line owing to the energization of the relay 27 which is energized by a circuit including the calling line and the transmitter bridge at the called station. If the desired line is in the act of being called by 50 another operator and the telephone receiver at the station of the desired line is still upon its switch hook the relay 27 would also be energized as a consequence of a circuit traceable from the grounded battery 9, the primary winding 34 of the link connector employed by the operator previously calling the desired line, the uppermost armature switch of relay 28 of the operator already 55 signaling the desired line, the alternate contact of the top armature switch of the relay 28 belonging to the operator first signaling the desired line, the tip of the associate plug G, the tip spring of the jack engaging this 60 plug, to the tip spring of the jack engaged 65

by the plug G employed by the operator second to seek the desired line, the top armature switch of the relay 28 of this second operator, the normal follow-up contact of this armature switch, the relay 27, the upper armature switch of relay 26¹, to ground by way of the right hand contact of this armature. Relay 26¹ having previously been momentarily energized, co-operates, when thus momentarily energized, with the energized 70 relay 27 to establish a circuit traceable from the grounded battery 9, the resistance 31, the lower armature switch of relay 29, the left hand contact of this armature switch, the lower armature switch of relay 26¹, the 75 contact of this armature switch, the armature switch of relay 27 and its alternate contact, the winding of relay 32, to ground. The relay 32 now establishes a locking circuit for itself traceable from its grounded 80 coil to its lowermost armature switch and contact, the lower armature switch of relay 29 and its right hand contact, the resistance 31, to the grounded battery 9. When the relay 29 is de-energized as previously de- 85 scribed the battery connection dropped by the lower armature switch of relay 29, is replaced at the right hand contact of the armature switch of relay 41¹. The intermediate armature switches of relay 32 energized under the conditions just described, 90 causes a busy tone to be transferred by the elements 48 and 49. The calling subscriber, upon connecting this busy tone to indicate that the desired line is busy, will restore his 95 telephone upon its switch hook to release relays 41 and 7 to restore the line equipment and the link connector equipment to idle condition. The plug G is freed from bridge 100 connections when the relay 32 is energized 105 so that the condition of the desired line is not modified by the equipment of an operator seeking connection therewith while a preceding operator is seeking or has secured connection therewith, the calling subscriber 110 taking no part in this result.

When the connection between subscribers has been broken the employed switch E remains in engagement with the contacts in connection with which it was previously brought, the wipers rotating in uniform directions and not being restored to normal, in the preferred embodiment of the invention.

When the relay P was energized, in the establishment of a connection between calling and called stations, its bottom armature switch engaged its alternate contact to close circuit through the wiper 50 of the left hand switch Q, the waiting contact engaged by this wiper and connected with the alternate contact of the bottom armature switch of relay P, the motor magnet R, the interrupter S¹, and the grounded battery 9, the motor magnet R thereupon stepping the shaft Q¹ 120 around step by step until the wiper 50 of the 125

left hand switch Q becomes engaged with a succeeding ungrounded waiting contact pertaining to an idle link connector. Wiper 51 moves together with wiper 50 and establishes a circuit for the lamp O pertaining to the idle link connector that has become associated with the wiper 50, the similarly positioned waiting contacts of the wipers pertaining to the same link connectors, there being as many waiting contacts as there are link connectors in an operator's group. If it is desired to have all the lamps O of idle link connectors lighted, switch elements 52 individual to the normal contacts of the bottom armature switches of relays P and individual to the different link connectors are brought into connection with contacts that are included in the signaling circuits, there being as many switches 52 as there are links in an operator's position and all of the switches being adapted for simultaneous engagement with their contacts through the agency of a magnet 53 controlled by an operator's push button T. To prevent the lamps from flashing while the wiper 50 is stepped around, the motor magnet R closes circuit through a sluggishly operating relay 54 whose right hand armature switch opens the circuit of the wiper 51. The operators are thus immediately directed to idle link connectors and will employ plugs G whether such plugs are in the jacks of telephone lines or upon the operator's plug board.

While I have herein shown and particularly described the preferred embodiment of my invention I do not wish to be limited to the precise details of construction and circuit arrangement shown as changes may readily be made without departing from the spirit of the invention.

Having thus described my invention I claim as new and desire to secure by Letters Patent the following:

1. A telephone exchange system including telephone lines extending to an exchange; link connectors at the exchange for uniting lines in conversation; calling line operated operators' responsive devices at different operators' positions; selector switches operable by calling lines for selecting responsive de-

vices that are free for selection; means for holding a succeeding or second operating responsive device hunting selector switch in position to connect the same responsive device with the calling line operating such succeeding selector switch; and operator controlled means for freeing the selected responsive device from the first selector switch and bringing it into connection with the second selector switch and thereby with the calling line operating the second selector switch.

2. A telephone exchange system including telephone lines extending to an exchange; link connectors at the exchange for uniting lines in conversation; operators' telephones at different operators' positions; selector switches operable by calling lines for selecting operators' telephones that are free for selection; means for holding a succeeding or second operating operator's telephone hunting selector switch in position to connect the same operator's telephone with the calling line operating such succeeding selector switch; and operator controlled means for freeing the selected operator's telephone from the first selector switch and bringing it into connection with the second selector switch and thereby with the calling line operating the second selector switch.

3. A telephone exchange system including telephone lines extending to an exchange; a group of link connectors at the exchange adapted to the use of an operator for connecting calling and called lines; signal devices for the link connectors of said group and having controlling electro-magnets; and means governed by equipment of the link connectors for causing said signal devices to operate when their link connectors are idle and to energize said magnets to restore the signal devices when their link connectors are taken for use.

In witness whereof, I hereunto subscribe my name this 31st day of March, A. D., 1913.

MORTON L. JOHNSON.
